UNITED STATES PATENT OFFICE.

GERARD H. GERAERDTS, OF NEW YORK, N. Y.

MOLD.

Application filed February 28, 1922. Serial No. 539,942.

To all whom it may concern:

Be it known that I, GERARD H. GERAERDTS, a citizen of the United States, and a resident of the city of New York, borough 5 of the Bronx, in the county of Bronx and State of New York, have invented a new and Improved Mold, of which the following is a full, clear, and exact description.

The present invention has relation to 10 molds particularly designed for the production of window sills constructed from cement, concrete, or other cementitious or plastic materials.

The present invention is more particularly concerned with a mold for the production of window sills provided on the upper face with an inclined depression constituting a drain and on the under face adjacent the outer end with a groove for preventing rain or water from passing over the 20 window sill from flowing onto the wall of the building.

As an object the invention aims to produce a mold of the character described which 25 embodies means for rendering the same adjustable to produce sills of various sizes.

In increasing or decreasing the size of the mold, it follows that the drain depression in the upper side of the mold must 30 necessarily be proportionately decreased or increased, and it is therefore a further object of the present invention to provide in connection with the mold a plurality of detachable drain depression forming elements 35 of various sizes which are capable of interchangeable association therewith.

Furthermore the invention contemplates in a mold of the character described a construction which affords means for effecting 40 the removal of the finished article without the necessity of waiting until the material has set and hardened, and this without danger of defacing or destroying the corners.

With the above recited and other objects 45 in view, the invention resides in the novel construction set forth in the following specification, particularly pointed out in the appended claims and illustrated in the accompanying drawings, it being understood 50 that the right is reserved to embodiments other than those actually illustrated herein to the full extent indicated by the general meaning of the terms in which the claims are expressed.

55 In the drawings—

Figure 1 is a plan view of a mold con-

structed in accordance with the invention and illustrating the same in set-up condition.

Fig. 2 is an end view thereof. 60

Fig. 3 is a transverse sectional view taken approximately on the line 3—3 of Fig. 1.

Figs. 4 and 5 are perspective views of the mold sections disassembled.

Fig. 6 is a perspective view of the drain 65 depression forming element removed.

Fig. 7 is a perspective view of a window sill constituting the article produced by the mold.

Fig. 8 is a transverse sectional view 70 thereof.

Referring to the drawings by characters of reference, 10 and 11 designate generally a pair of mold sections which are adapted to be adjustably associated with each other 75 for the production of window sills of various sizes. The mold section 10 includes a side wall 12 and an end wall 13, the former being provided at one extremity with a bracket 14 having a plurality of openings there- 80 through and the latter with a plurality of sets of openings 15 corresponding to the openings in the bracket, which openings when aligned receive the bolts 16 for rigidly attaching the end wall to the side wall at a 85 right angle to each other. The mold section 11 is provided with a side wall 17 and an end wall 18, the former having secured thereto at one extremity one leaf of a hinge 19, the opposite leaf 20 of which is adjust- 90 ably connected to the end wall 18 by means of bolts 21 passing through one of a plurality of sets of openings 22. This arrangement permits of the outward swinging of the end wall with respect to the side wall of 95 the mold section. The side walls 12 and 17 are each provided with longitudinally extending reinforcing angle iron strips 23 adjacent the upper and lower edges thereof and on the outer sides of the same. The side 100 wall 12 of the mold section 10 is provided adjacent the upper edge of its inner face with a longitudinally extending bead 24 parallel to the upper edge, which bead constitutes the means for forming the drip groove 105 in the lower face of the window sill. The lower edges of the end walls 13 and 18 of the mold members are arranged in the same plane with the lower edges of the side walls 12 and 17, while the upper edges of said end 110 walls are disposed in a plane slightly above the upper edges of said side walls. The

inner edges of the end walls are provided with inwardly projecting lugs 25 which are designed when the mold sections are assembled to overlie and engage with the upper 5 edge of the side wall of the opposite member. The inner edge of the end wall 18 is provided with a recess 26 adapted to snugly fit and accommodate the bead 24 on the side wall 12 of the mold section 10. The inner 10 edge of the end wall 13 of the mold section 10 is provided with a laterally projecting lug 27 on its outer side which affords a wider bearing surface when the inner edge of the end wall 13 is brought into contact with the 15 inner side of the side wall 17 of the mold section 11. The side walls 12 and 17 of the mold sections are provided on their outer sides with longitudinally extending bearing blocks 28 arranged between the reinforcing 20 angle iron strips, 23, the purpose of said blocks being hereinafter set forth. To set up or assemble the mold, the inner edges of the end walls 13 and 18 are respectively brought into contact with the inner sides of 25 the side walls 17 and 12, said end walls being first adjusted by means of the bolts 16 and 21 to obtain the proper relative spacing of the side walls 12 and 17 with respect to each other. It is understood that the sections 30 are assembled on any form of base 29 which serves as a bottom for the mold. The means for forming the inclined drain depression in the upper face of the window sill consists of a plate 30 provided with quarter 35 conical extremities 31 and having a flange 32 extending laterally from the upper edge thereof. The flange 32 is provided with longitudinally extending ears 33 from the opposite ends thereof. A U-shaped clamping 40 bar 34 is apertured at one extremity as at 35 to receive the outwardly projecting trunnion 36 for pivotally associating the same with the end wall of the mold sections, one clamp being provided with each of 45 said sections. The opposite extremity of the clamping bar is provided with an adjustable foot 37 and a cam lever 38 cooperating therewith for effecting adjustments thereof. To set up the mold, the end walls 50 are correspondingly adjusted with respect to the side walls of each mold section and the inner edge of said end walls are arranged contiguous or in abutting relation to the inner side of the side wall of the opposite section with the lugs 25 overlying the upper 55 edges of the side walls and with the bead 24 received in the recess 26. The drain depression forming plate 30 is then suspended by the flange 32 thereof from the upper edge 60 of the mold section 11 and the mold sections are shifted longitudinally to advance the end walls thereof toward each other until said end walls contact with the longitudinally extending ears 33 which serve as limiting 65 stops and as means for centering the plate 30. The clamping bars 34 are then swung on the pivot trunnions 36 to dispose the free ends over the outer side of the side walls. The cam levers 38 are then manipulated to advance and impinge the feet 37 against the 70 blocks 28 to lock and retain the mold in set up position. The plastic or cementitious material is poured into the mold and tamped down and smoothed off level with the upper 75 edges of the side walls. The side wall 12 with the bead 24 forms the lower face A of the sill B with the longitudinally extending groove C, while the side wall 17 together with the plate 30 forms the upper face D of the sill with the inclined drain depression 80 E. When the molding operation is complete, the cam levers 38 are released and the clamping bars 34 are swung to an out-of-the-way position. The end wall 18 of the mold section 11 is then swung outwardly on its 85 hinge 19 at an angle to permit of the removal of the mold sections from the completed article without defacing or destroying the corners. This permits of the removal of the mold without the necessity of waiting 90 until the sills have set and hardened, whereby the same mold may again be employed without loss of time. A plurality of drain depression forming plates of various lengths will be provided with each mold in order 95 that the depression and the spacing of the same from the opposite ends of the sill may be proportionately increased or decreased with the increases or decreases in the length and thickness of the sills to be produced. 100

I claim:

1. A mold for producing window sills constructed of plastic material comprising a pair of mold sections each of which includes a side wall and an end wall having an adjustable 105 connection therebetween, one of which constitutes a hinge for swingingly associating the side and end wall of one section with each other, means carried by the end wall of each section and engageable with the side wall of the opposite section for clamping the inner edges of said end walls against the inner sides of the side wall for locking the mold in set-up condition, and means for forming an inclined drain depression in the sill detachably suspended from the upper edge of the side wall of one section, said means comprising a plate having longitudinally extending ears from its opposite ends engageable with the end walls for spacing the end walls from 110 each other and for centering the said plate in the mold. 115
2. A mold for window sills comprising a pair of mold sections, each of which includes a side and end wall, and adjustable connection between the side and end walls of each section, one of which constitutes a hinge joint for permitting the outward swinging movement of the end wall with respect to the side wall, means carried by the end walls 125 130

- of said sections and engageable with the side walls of the opposite sections for clamping the inner edges of the end walls against the inner sides of the side walls, an inclined 5 drain depression forming plate having a flange at its upper edge engageable over the upper edge of one of the side walls for suspending the plate therefrom, and ears projecting longitudinally from the opposite ends 10 of the flange and engageable respectively with the end walls of the sections for relatively spacing the end walls from each other and from the opposite ends of the depression forming plate.
- 15 3. A mold for window sills including a horizontal base and a pair of mold sections adapted to be supported thereby, each of which includes a side wall and an end wall, a rigid adjustable connection between the 20 side and end wall of one section, a hinged
- adjustable connection between the side and end wall of the other section, means carried by said end walls and engageable with the side wall of the opposite section for impinging and clamping the inner edge of said end 25 walls against the inner side of said side walls, a drain depression forming plate having a flange at its upper edge engageable with the upper edge of one of the side walls for suspending said plate within the space defined 30 by the walls of the sections, longitudinally extending ears from the opposite ends of said flange engageable with the end walls for limiting the adjustment of the same toward each other and for centering the plate with- 35 in the molding space, and a bead provided on the inner face of the wall of the opposite section for forming a groove in the molded article.

GERARD H. GERAERDTS.
